UNITED STATES PATENT OFFICE

162,093

PLASTIC DISPLAY PACKAGE

Frederick William Steudler, Lancaster County, Pa.

Application January 3, 1950, Serial No. 6,989

Term of patent 14 years

(Cl. D80—5)

To all whom it may concern:

Be it known that I, Frederick William Steudler, a citizen of the United States residing in the county of Lancaster and State of Pennsylvania, have invented a new, original, and ornamental Design for a Plastic Display Package, of which the following is a specification, reference being had to the accompanying drawing, forming a part thereof:

Figure 1 is a perspective view of a plastic display package embodying my design;

Figure 2 is a front elevational view thereof;

Figure 3 is a side elevational view thereof;

Figure 4 is a plan view thereof; and,

Figure 5 is a bottom view thereof.

I claim:

The ornamental design for a plastic display package, as shown.

FREDERICK WILLIAM STEUDLER.
